UNITED STATES PATENT OFFICE.

JOSEPH W. FARR, OF OAK PARK, ILLINOIS.

ROOFING.

Application filed October 4, 1926. Serial No. 139,291.

My present invention relates to improvements in roofing and has special reference to the provision of an articulated roofing in which separate weather resisting elements, 5 similar to or corresponding with tiles, are secured together and reinforced in such a way as to permit of their being secured in final position in groups and so that they will have the requisite substantiality to sustain 10 the service required of them while the individual elements and the structure as a whole can be made of much more economical and lighter materials.

As is well known, tiles, and particularly 15 the variety of tile called "Spanish tile", which have a curved or undulating surface, are popular not only on account of their weather resisting properties, but also because of their appearance. Such tiles, however, are both heavy and comparatively 20 brittle. It is necessary, because of the brittle nature of the material of which they are formed, to give them a relatively heavy body, which entails a relatively heavy product. 25 And a relatively heavy roof structure must be provided for the support of the usual terra cotta or burnt tile. And even the ordinary burnt tile, notwithstanding its weight, is not infrequently broken and requires replacing.

As will hereafter be seen, the separate weather resisting elements of my structure may be made of relatively light material such as fabric or tissue or felting impregnated with asphaltum, a cement mixture or other cementitious material into the outer surface of which may be impressed granite or stone or mica flakes as is not an uncommon practice. The units so formed, as will 50 hereafter be seen, are articulated or secured together so as to reinforce the individual units and secure an assembly between them which is much more substantial and dependable than the assembly at present attained between the individual tiles of a tile roof as it is now made.

In order to attain the foregoing objects I have provided a structure illustrated in the accompanying drawing in which—

Fig. 1 is a plan of a section of articulated roofing constructed in accordance with my present invention.

Fig. 2 is an end elevation of the structure shown in Fig. 1.

Fig. 3 is a plan of a section of frame work upon which the tiles or covering elements

are to be mounted showing in dotted lines the relation of such a section to adjacent sections, and

Fig. 4 is an end view of the structure 60 shown in Fig. 3.

I have employed similar reference characters to designate similar parts throughout the several views.

While I have illustrated my articulated 65 roofing as provided in sections containing fifteen individual covering elements or tiles, it is obvious that either a larger or smaller number of covering elements or tiles could be grouped in a single section without in any 70 way departing from the principle of the structure herein described. Further, if temperature conditions permit it is preferable and feasible to install my roofing upon the rafters of the roofing of buildings directly 75 instead of covering such rafters first, as is now the general practice, with sheathing. For the assembly with the rafters of the 80 roofing aforesaid I provide, in the size of construction illustrated and described, three 85 lengths of material each designated by the character "A". This material may be suitable pieces of wood or metal, as may be desired, and they are set preferably slightly obliquely to the right lines of the structure 90 so that their ends may be staggered or slightly overlapped with like members of an adjacent section, shown in Fig. 3 in dotted lines and designated by the character "A'". Secured at equal intervals to the members 95 "A" are transverse members "B" which stand up from the plane of the members "A" a distance slightly less than the depth of the hollow formed by the curved inner surface of the tile elements. The members "A" and "B" may be secured together by nails or bolts or staples, as shown, or in any other desired way, it being understood that while a sturdy and dependable structure is desired, nevertheless the possibility of giving slightly without breaking is 100 highly desirable in all portions of a building and especially in the roofing. Secured along the tops of the members "B" are segmental elements "C" preferably moulded from 105 Portland or other hydraulic cement and reinforced with an insertion of fabric such as burlap or reticulated or woven metal. The curvature of the top of the member "C" is such as to conform to and fit with the inner 110 surface of the curved tile elements.

The curved tile elements "D" are prefer-

ably formed of fabric or tissue or felting impregnated with asphaltum or other suitable cementitious material, and as before stated, into the outer surface of which may be impressed flakes of stone or mica as is the present general practice in the production of asphalt shingles.

As will be noted in Fig. 2 one longitudinal edge "D" of the tile elements "D" is extended and carried into a slight reverse curve to extend under the edge of an adjacent tile section. The tile elements "D" are secured to the elements "C" by an asphalt or other suitable cement.

Such a roofing as is here described secures the individual tile elements together much more firmly than is the present practice in securing tiles to a roof and the central projecting portion of each tile element is so reinforced and supported as to be able to withstand not only the service that is required of a roofing, but also has sufficient strength to receive, without injury, a considerable blow and to support walking thereon as the unsupported edges of the tile elements are depressed and thereby withdrawn from ordinary contact.

It will also be evident that my structure is much lighter than a roofing formed of burnt tile and is not only not brittle, but is so constructed that slight movement between the tile members or flexibility in the structure is easily possible without any impairment of the roofing.

By securing a number of the individual tile elements together in factories where the

work may be done most expeditiously and economically, considerable expense in installing the tile upon the roof of a building is saved.

Having described my invention what I claim as new and desire to secure by Letters Patent is—

1. An articulated roofing comprising a plurality of weather resisting elements of asphalt composition of curvilinear transverse conformation, a series of upstanding parallel supports, caps of cementitious material secured to said supports and entering the reverse depressions of and secured to said tile elements, and transverse base members disposed parallel with each other and obliquely with said supporting members secured to said supporting members.

2. An articulated roofing comprising base members, transversely disposed parallel supporting members secured to said base members, caps of reinforced concrete secured to said supporting members, and a plurality of flexible curvilinear tile elements resting upon and secured to said caps having an edge extending under laterally adjacent tile elements.

3. An articulated roofing comprising base members, transversely disposed parallel supporting members secured to said base members, a plurality of asphalt composition tile elements, and concrete members inserted between, conforming with, and secured to said supporting and tile members.

JOSEPH W. FARR.
